UNITED STATES PATENT OFFICE.

EDWARD J. FINK, OF SYCAMORE, ILLINOIS.

BIFOCAL LENS.

1,117,990.

Specification of Letters Patent. Patented Nov. 24, 1914.

Application filed November 16, 1910. Serial No. 592,687.

To all whom it may concern:

Be it known that I, EDWARD J. FINK, a citizen of the United States, residing at Sycamore, in the county of Dekalb and State of Illinois, have invented certain new and useful Improvements in Bifocal Lenses, of which the following is a specification.

My invention relates to bi-focal lenses and to the method of making such lenses, and has for its object to produce a bi-focal lens, preferably in a single piece which shall have both the distance and reading fields relatively large and so arranged with reference to each other than the user shall not only be inconvenienced as little as possible by the presence of the two lenses in the same structure but shall have a lens, the reading field or portion of which in no way interrupts or projects into the distance field, which is itself of oblong shape and corresponds to the normal field of distance vision.

Referring to the drawings, Figure 1 shows a plan, side and end view of an ordinary lens blank; Fig. 2 shows a plan and sectional side and end view of the blank after the first grinding operation; Fig. 3 shows a plan and sectional side and end view of the blank after the second grinding operation; Fig. 4 shows a plan and sectional side and end view of the blank after the concave side of the lens has been ground; Fig. 5 is a plan view of the lens, some of the various shapes which the reading field may take being indicated in dotted lines; Fig. 6 is a diagram showing the convex surface of the lens after that surface has been ground, the radii of curvature of the several surfaces of a specific example being indicated on the axes of 90° and 180°. Fig. 7 is a similar view of the concave surface of the lens similarly marked; Fig. 8 is a similar diagram showing the resulting optical effect of the combination of the convex and concave surfaces shown in Figs. 6 and 7, and Figs. 9, 10 and 11 show various forms which may be given to the reading field.

In producing my bi-focal lens, a lens blank A as shown in Fig. 1 is first subjected to a grinding action to simultaneously produce thereon generated surfaces whose radii in planes at right angles to each other are or may be different. Thus the curve 1 which may be taken as along the 90° axis of the lens may be of +7.5 diopters, while the 55 curve 2 which may be taken as along the 180° axis may be of +6.0 diopters. The so-

ground blank is then subjected to a second grinding to produce thereon surfaces of curvature suitable for the distance field of the lens; as for example a surface 3, along the 90° axis having a power of +6 diopters and a surface 4 along the axis of 180° as of +4.5 diopters. As the result of these two grindings there is produced a bi-focal lens having an elliptical, oval, or oblong distance field, surrounded by an area having a suitable curvature for the reading field. The lens may then be completed by grinding the reverse side concavely to produce surfaces having along the 90° axis, a power of, say, -5.0 diopters, and a power along the 180° axis, say, of -3.5 diopters.

The resulting lens will as shown in Figs. 4 and 8 have an oblong distance field having the optical power due to a curved surface of +1.0 diopter along both axes, this distance field being surrounded by a reading field having a power of +2.5 diopters on both axes.

It is to be understood that the specific example here given is intended for illustration only, as it is obvious that these curves may be varied to produce distance and reading fields of any desired curvature, and it is this feature which constitutes one of the great advantages of my invention, viz., that in a bi-focal lens both reading and distance portions may each be not only such as to independently correct for near or far sightedness, but may also be curved to independently provide for the correction of astigmatism or decentered to provide for prismatic correction.

The distance or reading field may be decentered for purposes of prismatic correction by properly inclining or tilting the lens-blank support with reference to the grinding tool and such decentering may be applied with equal facility to either the distance or reading field independently of each other.

The above described compounding of the optical effect of the different surfaces is diagrammatically illustrated in Figs. 6, 7 and 8, the power along the 90° and 180° axes, in diopters being marked.

As will appear from Fig. 6, the distance field is a surface of compound curvature resulting from a simultaneously grinding on two cylindrical surfaces of respectively +4.5 diopters (180° axis) and +6 diopters (90° axis); while the reading field is the

surface resulting from simultaneous grinding of surfaces of +6 diopters (180° axis) and +7.5 diopters (90° axis).

Fig. 7 represents the concave side ground simultaneously along the 90° and 180° axes on curves or surfaces of -5 and -3.5 diopters respectively.

Fig. 8 shows the resultant lens having a distance field with an effective curvature of +1 diopter and a reading field of +2.5 diopters.

It will be noted that by my method of grinding an oblong distance field is provided, which provides for the normal extent of distance vision and that with such oblong distance field is associated a reading field which may extend along the whole edge of the distance field, so that in neither distance nor near seeing is there any lateral intrusion or reentrance of one field into the other.

The lens blank may as indicated in Fig. 5 and in Figs. 9, 10 and 11 be cut so as to leave the reading field of a wide variety of shapes. In Figs. 9, 10 and 11, D indicates the distance field and R the reading field. The distance field has been shown in the various figures as surrounded by a dotted line, but in the actual lens, this line is practically invisible.

In the above described example, the concave side of the lens has been shown as having a surface of double curvature, but the result desired may be equally effected by using a simple cylindrical surface; thus if surface 1 be of +7.5 diopters and surface 2 of +2.5 diopters, and surface 3 of +6 diopters and surface 4 of +1.0 diopter, the concave side of the lens may be ground as a plain cylinder having a power of -5.0 diopters on the 90° axis, the line of section on the 180° axis being, of course, a straight line. The resulting lens would have an oblong distance field having the optical power due to a curved surface of +1.0 diopter along both axes, and a reading field having the power of +2.5 diopters along both axes.

Other modes of combining the curvatures of the two surfaces will readily suggest themselves to those familiar with the art.

The curvatures, as shown in the drawings, have been distorted to more clearly indicate the relations of the surfaces to each other.

I claim:

1. A bi-focal lens ground from a single piece of glass having an uninterrupted oblong distance field and a reading field extending along one edge of the distance field, the surfaces of different curvature merging into each other without abrupt angles.

2. A one-piece bi-focal lens ground from a single piece of glass having an uninterrupted oblong distance field and a reading field extending along practically the length of one edge of the distance field, the surfaces

of different curvature merging into each other without abrupt angles.

3. A one-piece bi-focal lens ground from a single piece of glass having an uninterrupted oblong distance field and a reading field extending along one edge of the distance field, the surfaces of different curvature merging into each other without abrupt angles.

4. A one-piece bi-focal lens ground from a single piece of glass having an uninterrupted oblong distance field and a reading field extending along practically the length of one edge of the distance field, the surfaces of different curvature merging into each other without abrupt angles.

5. A bi-focal lens having a convex face made up of a distance field and a reading field, each field having a surface of different dioptric curvature along planes at an angle to each other.

6. A bi-focal lens having a convex face made up of a distance field and a reading field, each field having a surface of different dioptric curvature along planes perpendicular to the plane of the lens at an angle to each other, and a concave face.

7. A bi-focal lens having a convex face made up of a distance field and a reading field, each field having a surface of different dioptric curvature along planes perpendicular to the plane of the lens at an angle to each other, and a concave face, the curvatures of the convex and concave surfaces being so proportioned that distance and reading fields have the desired power for the area of their respective fields.

8. A bi-focal lens ground from a single piece of glass whose reading field does not reenter into the distance field, the surfaces of different curvature merging into each other without abrupt angles.

9. A one-piece bi-focal lens ground from a single piece of glass whose distance field is oval, and whose reading field does not re-enter into its oval distance field, the surfaces of different curvature merging into each other without abrupt angles.

10. The process of making bi-focal lenses, which consists in simultaneously grinding a blank to produce a convex surface having in planes at an angle to each other different dioptric radii, then further grinding the blank to produce thereon a second convex surface having in planes at an angle to each other dioptric radii differing from each other and of lengths different from the corresponding radii of the first surface.

11. The process of making bi-focal lenses, which consists in simultaneously grinding a blank to produce a convex surface having in planes at an angle to each other different dioptric radii, and then further grinding the blank to produce thereon a second convex surface having in planes at an angle to each other

each other different dioptric radii of greater length than the corresponding radii of the first surface, thereby producing an oblong distance field surrounded by a reading field, 5 and then grinding the reverse side of the blank to form a concave surface.

12. The process of making bi-focal lenses, which consists in simultaneously grinding a blank to produce a convex surface having 10 in planes at an angle to each other different dioptric radii, then further grinding the blank to produce thereon a second convex surface having in planes at an angle to each other different dioptric radii of greater 15 length than the corresponding radii of the first surface, thereby producing an oblong distance field surrounded by a reading field.
13. The process of making bi-focal lenses, which consists in simultaneously grinding a 20 blank to produce a convex surface having in planes at an angle to each other different dioptric radii, then further grinding the blank to produce thereon a second convex surface having in planes at an angle to each 25 other different dioptric radii of greater length than the corresponding radii of the first surface, thereby producing an oblong

distance field surrounded by a reading field, and then grinding the reverse side of the blank to form a concave surface. 30

14. The process of making bi-focal lenses, which consists in simultaneously grinding a blank to produce a convex surface having in planes at an angle to each other different dioptric radii, then further grinding the 35 blank to produce thereon a second convex surface having in planes at an angle to each other different dioptric radii of greater length than the corresponding radii of the first surface, thereby producing an oblong 40 distance field surrounded by a reading field, and then grinding the reverse side of the blank to form a concave surface, the curvatures of the concave and convex surfaces being so proportioned that the distance and 45 reading fields have the desired power over the area of their respective fields.

In testimony whereof, I affix my signature in presence of two witnesses.
